R. C. MICHAELS & A. F. HUMPHREY,
TANK VALVE,
APPLICATION FILED FEB. 19, 1917.

1,274,924.

Patented Aug. 6, 1918.

UNITED STATES PATENT OFFICE.

RAYMOND C. MICHAELS AND ALEXANDER F. HUMPHREY, OF PITTSBURGH, PENNSYLVANIA, ASSIGNEES, BY DIRECT AND MESNE ASSIGNMENTS, OF ONE-FIFTH TO SAID HUMPHREY, THREE-FIFTHS TO SAID MICHAELS, AND ONE-FIFTH TO WILLIAM L. SWARTZ, OF PITTSBURGH, PENNSYLVANIA.

TANK-VALVE.

1,274,924.

Specification of Letters Patent. Patented Aug. 6, 1918.

Application filed February 19, 1917. Serial No. 149,588.

To all whom it may concern:

Be it known that we, RAYMOND C. MICHAELS and ALEXANDER F. HUMPHREY, citizens of the United States, residing at N. S. Pittsburgh, in the county of Allegheny and State of Pennsylvania, have invented certain new and useful Improvements in Tank-Valves, of which the following is a specification:

10 This invention relates to new and useful improvements in tank valves.

The primary object of the invention is the provision of a float controlled valve for tanks, such as flush tanks adapted for rendering their operation substantially noiseless by preventing vibration as well as chattering and the well-known "water-hammer".

A further object of the invention is to provide a flush tank inlet valve of the float controlled variety arranged for deadening or muffling all noise incident to the operation of the valve, both in connection with the movable parts thereof as well as the force of the incoming water.

25 A still further object of the device is the provision of an intake valve that is easy and inexpensive to manufacture, being made up of interchangeable, readily assembled parts, provision being made for the noiseless 0 passage of the water through it, the final force of the same being cushioned by contacting means provided with the structure.

With these general objects in view and others that will appear as the nature of the 35 invention is better understood, the same consists in the novel combination and arrangement of parts hereinafter fully described, illustrated in the accompanying drawings, and thereafter claimed.

40 In the drawing forming a part of this application and in which like designating characters refer to corresponding parts throughout the several views:—

Figure 1 is a vertical central sectional view through the device, parts being shown in elevation and broken away.

Fig. 2 is an elevational view of the valve plunger removed.

Fig. 3 is a transverse sectional view taken 50 on line A—B of Fig. 1.

Fig. 4 is a top plan view of the valve seat and retainer.

Fig. 5 is an elevational view of the valve cage with the ball valve therein, and

Fig. 6 is a view partially in section of a 55 slightly modified form of valve plunger.

It being understood that the present device relates to intake valves for any form of tanks, the same is herein illustrated as broadly consisting of a cup or goblet-shaped 60 casting 1 having an axial inlet bore 6 through the stem standard 38 and mounted upon the bottom 34 of the tank in axial alignment with the inlet water pipe 35 by means of any desirable form of pipe coupling such as 65 36 herein illustrated which is removably secured to the bottom 34 by a lock nut 37, a float 32 being arranged for the automatic actuation of the valve in controlling the opening and closing of the water inlet 6. 70

A valve seat 2 is maintained within the central recess 39 in the bottom of the cup portion 40 of the casting by means of a cap nut 4, a packing 5 being preferably interposed between the said valve seat and nut. 75 Longitudinal grooves 3 are arranged within the central passage 41 of the valve seat 2 designed to assist the smooth passage of water therethrough.

A tubular upper extension 8 is threaded 80 within the casting cup 40, arranged with an axial chamber 42 within which the valve or plunger 43 is slidably mounted, it being understood that a cage 20 is threaded to the lower end of the extension 8 adapted for 85 also receiving the plunger 43 therein, the lower end of the cage having an inner annular flange 44 arranged around and in spaced relation with respect to the upper inner outlet end of the valve seat 2. 90

The plunger 43 is formed in sections, the upper section 11 of which provides the valve stem 45 slidably arranged through the top opening 46 of the extension 8, a stuffing box 9 being arranged therefor provided with a 95 packing 10 of the usual form. An angular supporting arm 28 projects upwardly from the extension 8 and is provided with a rod 30 pivoted thereto as at 29, the said rod being operatively connected to the valve stem 45 by means of a link 33 while a suitable float 32 is carried by the free outer end of the said rod 30. An L 81 is provided on the rod 30 for use in connecting the float

therewith for service in either a high or low tank if required.

A ball valve 19 is arranged for limited movement within the cage 20 and is formed of rubber, porcelain, brass or other desirable material being adapted for assistance in seating by reason of its own weight. A middle section 12 is threaded to the upper section 11 of the plunger 43, having a bolt 10 slidably arranged therethrough axially of the plunger and provided with a squared head 47 arranged within the rectangular chamber 16 in the bottom of the section 11 while a packing 17 is interposed between 15 the head 47 and the upper end of the chamber 16.

A lower section 13 is secured beneath the section 12 and a packing 18 is also secured there-between by means of a screw 15 threaded into the lower end of the bolt 18, a concaved face 48 being provided in the lower end of the section 13 adapted for engaging the ball 19.

An apron 22 in the form of an annular depending flange, is externally threaded upon the upper or rim portion 49 of the casing cup 40 and is provided with an annular washer or packing 24 seated within the inner face thereof, an annular chamber 26 being thereby provided between the packing 24 and the outer face of the cup 40. Any desired number of perforations 7, 7^a are provided through the cup 40 for outletting the water therefrom, the water thereafter entering the tank from the valve through the annular outlet 27 at the bottom of the chamber 26. A laterally projecting lug 23 is carried by the apron 22 having a passage therethrough connecting with the chamber 26 being adapted for the mounting 40 of a refill pipe 25 when the valve is employed in a low form of tank.

The operation of the device will be apparent from this description thereof, the opening and closing of the valve seat passage 41 being controlled by the ball valve 19 and the float operated plunger 43, the water passing through intake 6 and the seat 2 enters the casing chamber 21 by passing around and 50 through the cage 20. The outlet ports 7 and 7^a, unitedly provide a greater diameter for the out-flowing water from the casing 1 than that afforded by the intake passage 41 of the valve seat whereby the force of 55 the water is greatly diminished as it passes through the ports 7, 7^a. The streams of water from these ports strike against the packing 24, serving as a sound insulator and rendering the outflow substantially noiseless, 60 the water then passing downwardly from the chamber 26 and through the annular outlet 27 into the tank.

The provision of the plunger valve 43 built up in the manner described, is adapted 65 to eliminate vibration usually transmit-

ted between metallic bodies by the interposing of the washer 18 and the employment of the packing 17. The bottom section 13 is normally slightly spaced from the section 12 a greater distance than the thickness of 70 the packing 18 while the pressure of the inflowing water is first exerted upon the lower section 13 which is yieldingly arranged with respect to the remaining elements of the plunger thereby taking up the vibrations 75 and preventing what is commonly termed "chattering". All upward movement of the section 13 is thereby cushioned and it will be understood that the bolt head 47 being squared and arranged within the correspondingly shaped chamber 16, any relative rotation between the sections 12 and 13 is prevented. The packing 17 is adapted to cushion the head 47 when the packing 18 has become worn and reduced in thickness. 80

In Fig. 6 the plunger 43 is illustrated partially in section and employing a 2 part lower section 13^a, 13^b in place of the lower section 13 heretofore described, the said two sections being secured to the bolt 14 in the same manner by an elongated screw 15'. The section 13^a is threaded upon the bolt 14, while the section 13^b is secured at the lower end thereof and is provided with a tapered lower face 48'. It will be understood that 95 when the form of plunger is employed, as shown in Fig. 6, the ball 19 will be omitted as the conical face 48' of the lower section 13^b thereof is adapted to rest upon the valve seat 2 upon the closing of the valve. 100

What is claimed as new is:—

1. A valve comprising a goblet-shaped casing having an inlet passage in the stem portion thereof and a plurality of relatively small ports through the wall of the cup portion of the same, an extension carried by the cup portion of said casing having an axial bore, a cage depending from the extension and arranged within said cup portion, and a freely movable cushioned reciprocating controlling means for said inlet passage arranged within said bore and said cage. 105

2. A valve comprising a goblet-shaped casing having an inlet passage in the stem portion thereof and a plurality of relatively small outlet ports through the wall of the cup portion of the same, an extension carried by the cup portion of said casing having an axial bore, a cage depending from the extension and arranged within said cup portion, a valve seat member secured in the bottom of said cup portion extending inwardly of the cage and having a passage therethrough in alignment with said inlet 120 passage, and a cushioned reciprocating float controlled means for closing said valve seat passage. 125

3. A valve comprising a goblet-shaped casing having an inlet passage in the stem 130

- portion thereof and outlet ports through the wall of the cup portion of the same, an extension carried by the cup portion of said casing and having an axial bore, a cage depending from the extension and arranged within said cup portion, a valve seat member secured in the bottom of said cup portion and having a passage therethrough in alignment with said inlet passage, an annular depending apron carried by said cup portion of the casing forming a chamber between said cup portion and apron with an annular outlet at the lower end thereof, a sound insulator carried by the inner face of said apron outwardly of the said ports, and a reciprocating controlling means for said valve seat arranged within the bore and said cage.
4. A valve comprising a goblet-shaped casing having an inlet passage in the stem portion thereof and outlet ports through the wall of the cup portion of the same, an extension carried by the cup portion of said casing having an axial bore, a cage depending from the said extension within said cup portion, a valve seat member secured in the bottom of said cup portion extending inwardly of the cage and having a passage therethrough in alignment with said inlet passage, an annular depending apron carried by said cup portion of the casing, forming a chamber between said cup and apron with an annular outlet at the lower end thereof, a sound insulator carried by the inner face of said apron outwardly of the said ports and a shiftable cushioned controlling means for said valve seat arranged within the said bore.
5. A valve comprising a cup casing having an inlet in the bottom thereof and radial outlets through the sides of the same, a tubular extension carried by said casing, a cage depending from said extension, a valve loosely and shiftably arranged within the said cage, a cushioned plunger shiftably arranged within said extension and cage and controlling means for said plunger.
6. A controlling plunger for valves, comprising an upper section having a rec-
- tangular chamber in the bottom thereof, a packing at the inner end of said chamber, an intermediate section carried by said upper section, a bolt slidably arranged through said intermediate section with a squared head positioned within said chamber adjacent said packing, a lower section secured to said bolt having a bottom engaging face and a shock-absorbing washer carried by the bolt between said lower and intermediate sections.
7. A reciprocating valve plunger comprising an upper section, an intermediate section rigidly and removably secured thereto, a lower section shiftably attached to said intermediate section and having a bottom engaging face, a cushioning member arranged between said intermediate and lower sections, the said intermediate and lower sections being normally separated a greater distance than the thickness of said cushioning member.
8. A plunger member comprising an upper socketed section, an intermediate section removably attached to said upper section, a cushion within said socket, an attaching member comprising a bolt shiftably carried by said intermediate section, normally spaced from the said cushion, a lower section having an engaging face secured to the said bolt and resilient means upon said bolt between said intermediate and lower sections, the said bolt being adapted for engagement with said cushion upon the reduction in thickness of said resilient member during the wearing of the device.
9. A sound-reducing valve structure comprising a cup casing having an inlet passage and radial outlet ports, a cylindrical sound insulation means arranged outwardly of said ports, a valve for said inlet passage, a plunger arranged adjacent said valve, the said plunger being formed of loosely connected sections and sound cushioning members between the sections of the plunger.

In testimony whereof we affix our signatures.

RAYMOND C. MICHAELS.
ALEXANDER F. HUMPHREY.
